UNITED STATES PATENT OFFICE.

JOHN B. GURY, JR., OF ST. LOUIS, MISSOURI.

STITCHING MACHINE.

Application filed October 9, 1926. Serial No. 140,623.

This invention relates to stitching machines and more particularly to such machines that are used for marking cloth in the manufacture of clothing and other commodities where several pieces of the same pattern are cut from a pile of several layers of cloth.

In the manufacture of garments in quantity production, it is customary to lay upon a 10 table a pile of cloth consisting of several layers and marking upon the topmost layer the outline of the pattern to be cut and then cutting through the entire pile and simultaneously producing a multiplicity of like pieces 15 by using an electric or other motor-driven cutting machine that is manipulated by the operator to follow the lines of the pattern as marked on the topmost layer as above stated.

In order to mark the several pieces for the 20 location of buttons, buttonholes and pockets, and for other indications, it is quite a common practice to stitch through the pile of cloth at the respective places to be marked with a relatively long piece of thread and leaving it 25 either in a single strand or looped double through the entire pile of cloth, and then, after the respective places have been so stitched, the several layers of the cloth are separated and a portion of the strand or loop 30 of thread is severed on either side of the respective layers, so that each layer has a fragment of the thread therethrough and extending on each side thereof, which fragments are easily pulled out when no longer required.

The present invention has for its principal 40 object to produce a simple, practical and efficient machine for stitching the cloth for the above noted purpose; to secure precision and positive action with ease of operation of the machine; to provide for the ready release of the loop catching device of the machine without necessitating a manual operation of any associated actuating element of said device; 45 and to attain certain advantages as will more fully appear in the following description.

The invention consists in the novel construction and arrangement of the machine as a whole and the parts and combinations and 50 arrangements of parts thereof, all as herein-after described and afterwards pointed out with particularity in the appended claims.

In the accompanying drawings forming 55 part of this specification and illustrating a practical adaptation of the invention—

Figure 1 is a side elevation of the machine

with the parts in normal or unoperated position;

Figure 2 is a top plan view of the base-plate of the machine, with the upper standard 60 thereof being shown in cross section on the line 2—2 of Figure 1;

Figure 3 is an inverted plan view of the base-plate, showing the loop-catcher and its cooperative elements in normal or unoperated 65 position;

Figure 4 is a view similar to that shown in Figure 1, the operating handle being depressed and the actuatable parts of the machine being accordingly shown in operated 70 position;

Figure 5 is a view on an enlarged scale, partly in vertical section and partly in side elevation, showing the details of the reciprocating needle-carrier and the arrangement 75 of the cooperating presser-foot and its reciprocating carrier and locking device therefor;

Figure 6 is a cross section taken on the line 6—6 of Figure 5;

Figure 7 is a cross section taken on or about the line 7—7 of Figure 5;

Figure 8 is a cross section on the line 8—8 of Figure 5;

Figure 9 is a top plan view of the presser- 80 foot, the carrier-bar thereof being shown in cross section and the line of section being taken just above the presser-foot;

Figure 10 is a fragmentary view illustrating, on an enlarged scale, the details of the 90 locking element for the carrier-bar of the presser-foot;

Figure 11 is a fragmentary view, on an enlarged scale and in longitudinal section substantially on the line 11—11 of Figure 2, and 95 showing the loop-catcher and its cooperating adjacent parts in normal or unoperated position;

Figure 12 is an inverted plan view of the parts as shown in Figure 11;

Figure 13 is a view similar to Figure 12, but showing the loop-catcher in its forward position at the completion of the downward stroke of the operating lever of the machine;

Figure 14 is a view similar to Figures 12 105 and 13, but showing the loop-catcher in its forward position to release the loop of the stitching thread, to which position it may be pulled by the looped thread in the hand of the operator;

Figure 15 is an inverted plan view of the rear end portion of the base-plate of the ma-

chine, showing the relative positions of the actuating and controlling elements for the loop-catcher when the latter is in its operated position as shown in Figure 13;

5 Figure 16 is a view similar to Figure 15, but showing the relative positions of the parts when the loop-catcher is in the position shown in Figure 14;

10 Figure 17 is a view similar to Figures 12, 13 and 14, but showing a modification of the loop-catcher;

15 Figure 18 is a fragmentary detail view, on an enlarged scale and partly in section and partly in side elevation, showing a modification of the operating lever and cooperating parts of the machine, said parts being in their normal or unoperated position; and

20 Figure 19 is a similar view, the parts being shown in operated position.

25 Referring now to the drawings, the numeral 1 designates the base-plate of the machine, which is made hollow and is open on its under side, and being stiffened by longitudinal and transverse ribs 2, 3, respectively, as more clearly shown in Figure 3 of the drawings.

Secured on the base-plate 1, as by screws 4, preferably inserted from the bottom, as shown more clearly in Figure 3, is a standard 30 5 extending upwardly from the rear end portion of said base-plate and having a forwardly extending, substantially horizontal arm 6. At the forward end of said arm 6 is a head portion 7 having flat top and bottom faces 35 and rounded end portion 8 (see Figure 8 of the drawings), said head portion 7 having a bore 9 therethrough (see Figures 5 and 8).

Secured, as by screws 10, to the under side 40 of said head portion 7, is a plate 11 having a cylindrical upward extension 12 located axially in said bore 9 and being of considerably smaller diameter than said bore; and fitted tightly over said cylindrical extension 45 12 is a tubular member 13 which extends some distance above the head portion 7 and serves as a guide for a second tubular member 14 that is sleeved on said member 13 so as to slide freely thereon, there being an annular 50 space between the lower end portion of said tube 13 and the wall of the bore 9 of sufficient dimensions to receive the lower end portion of said tube 14 when the latter is moved to its lowermost position during its operation 55 as will be later described.

It is to be here understood, of course, that said tubular member 13 is fastened securely to said cylindrical extension 12 of the plate 11 by pinning, welding, or other approved 60 or practical methods, and by the same process a bushing 15 is secured within the upper end portion of said tubular member 14. This bushing 15 is internally screw-threaded for the reception of a screw-threaded plug 16, preferably having a knurled, annular, outer

collar portion 17 for convenience in placing said plug in and removing it from said bushing 15. This structure is best shown in Figure 5.

Secured axially in said plug 16 is a needle-carrier comprising a bar 18 in whose lower end portion is secured a needle 19. Normally, in the uppermost position of said bar 18, the lower end portion of the bar is supported and guided by a bushing 20 that is secured within the upper portion of said tubular 70 13. When said bar 18 is lowered, its lower end portion passes through a second bushing 21 located approximately midway between said bushing 20 and said cylindrical 75 extension 12 of the plate 11, which latter is provided with an axial bore 22 of the same diameter as the bores of said bushings 20 and 21, all being such that said bar 18 will slide 80 readily through them.

In the raised position of the bar 18 the lower end portion of the needle 19 projects a short distance below the bottom of said plate 11 and through a guide aperture 23 (see Figure 9) in an arm 24 of a presser-foot 25, which latter has an annular foot portion proper 26 that is split, as at 27, with an opening sufficiently wide to permit the stitching thread to be passed therethrough, as will be later 90 more fully described in connection with the 95 operation of the machine.

Sleeved on the tubular member 14 is a member comprising an annular lower end portion 28 and a split annular upper portion 29 that are connected on opposite sides of said tube 14 by parallel longitudinal members 30, said longitudinal members 30 having diametrically-disposed, transverse apertures 31 for the reception of trunnions 32 of an operating lever 33, to be presently more fully 105 described. The split upper portion 29 is provided with apertured ears 34, one of which is screw-threaded, and said portion 29 is clamped to the tube 14 by a screw 35 that is applied so as to draw said ears 34 together. In this way the said member is capable of 110 adjustment on the tube 14, yet it may be readily secured in place.

The portion 29 has a rearward extension 36 that is bifurcated as by grooving it rectangularly (see Figure 6 of the drawings) so as to receive, with a sliding fit, a carrier-bar 37, of correspondingly rectangular cross-section, which has the presser-foot 25 secured to its lower end portion, said bar 37 being retained 115 in the bifurcated portion 36 of said member 29 by a plate 38 that is held in place by screws 39.

The bar 37 has a transverse stop-pin 40 which is normally held yieldably against the upper side of the extension 36 of the member 29 by a spring 41 whose lower end portion is attached to a pin 42 projecting from the plate 38 and whose upper end portion is attached to an angular extension 43 of a rod 44 ex- 120 125 130

tending upward from the end of said bar 37 (see Figure 5 of the drawings).

Coiled around the carrier-bar 37 is a spring 45 that is interposed between the extension 5 36 of the member 29 and the top side of the head portion 7 of the standard arm 6 and is always under compression so as to yieldably hold the tubular member 14 and the operating lever 33 in normal or raised position, 10 acting to restore them to such position after each operation thereof, the presser-foot 25 coming in contact with the under side of the plate 11 serving as a stop for limiting the upward movement of said bar 37 and also that 15 of the tube 14 owing to the arrangement of the stop-pin 40 that is engaged by said extension 36 of the member 29. The presser-foot, as shown more clearly in Figures 5 and 9, is provided with a vertically grooved portion 20 46 to fit the bar 37 and is detachably secured to said bar by a screw 47.

The operating lever 33 has an open frame or yoke portion 48 surrounding said carrier-bar 37 and tubular member 14, and in the 25 side members of said frame or yoke portion are secured the above mentioned trunnions 32 which, as shown, comprise pins or studs that are inserted in apertures provided therefor in said frame or yoke side members, said 30 pins or studs being secured in place by set-screws 49, as shown in Figure 7. At the outer end of said operating lever 33 is a handle portion 50 to be grasped by the operator in manipulating the machine, while the 35 inner end portion of the lever is fulcrumed, as by a pivot stud or bolt 51, on a bracket extension 52 of the arm 6 of the standard 5.

In order to provide for the straight up and down movement of the trunnions 32 in the 40 yoke portion 48, the operating lever 33 is made telescopic between the axis of said trunnions 32 and the fulcrum 51, by having a tubular section 53 fitted and secured tightly on a stem extension 54 as by a cross-pin 55 45 or other suitable means, in which tubular section 53 is slidably fitted a stem extension 56. By this construction and arrangement an easy up and down reciprocatory movement of the tubular member 14 on the guide tube 13 50 is accomplished by the operator depressing the lever 33 against the action of the spring 45 which returns the parts to normal position when the lever is relieved of the downward pressure by the operator.

55 As the operating lever is depressed the needle 19 and the presser-foot 25 move downward simultaneously in their normal relation as shown in Figures 1 and 5, and continue in such relation until the presser-foot 60 comes in contact with the pile of cloth, whereupon the spring 41 will yield and permit the tubular member 14 to continue on and drive the needle through the pile of cloth, thereby carrying a loop of the stitching thread 65 through the pile and thence through an

opening 57 in the base-plate 1, the point of the needle reaching close to the face of the work table at the completion of the stroke. In this connection, it may be here stated that the stitching thread may be taken from any 70 suitable source of supply, and the strand, of course, is threaded through an eye provided in the needle near its point, in a manner similar to any other sewing needle.

As shown in the drawings (see Figures 1 75 and 4) the stitching thread, indicated by the numeral 58, is supplied from a spool 59, as indicated by the dotted lines, which is rotatable on a rod or stem 60 projecting upward from the standard 5, said spool resting on a disk 61 at the base of said rod or stem 60, and the thread being carried from the spool through an eye 62 located above the latter and at the end of a wire bracket member 63. From the eye 62 the thread may be passed 80 through another eye 64 on the upper side of the arm 6 of the standard 5 near the outer end of said arm, and thence directly to the eye of the needle or, obviously, over or through an additional guide (not shown) 85 between the needle and said eye 64, as may be desirable.

Mechanism for catching and holding the 90 loop of the stitching thread at the under side of the base-plate 1 will now be described.

On the under side of the base-plate 1 is a 95 longitudinally slidable, flat bar 65 which is supported by two guide-plates 66, which latter are secured in place by screws 67 (see Figures 3, 11 to 13, and 15 to 17, inclusive). This bar is normally held yieldably in retracted position by a spring 68 which is secured at one end to a stud 69 on said bar and at its opposite end to a stud 70 on said base-plate 1. Pivotally secured on the forward 100 end portion of said bar 65 is the catcher element 71, which latter, in the construction illustrated in Figures 3, and 11 to 14, inclusive, has a stud 72 thereon, to which is attached one end of a spring 73 whose opposite end is attached to a stud 74 on said bar 65. This spring 73 acts to yieldably hold the catcher element 71 in its normal retracted 105 position against a stop-pin or stud 75 on the base-plate 1, and said catcher element 71 during its respective actuations, to be presently described, swings about its pivot 76, which latter, as shown, comprises a shoul- 110 dered stud that has its middle portion rotatably fitted in an aperture provided therefor in said bar 65 and its end portion either screw-threaded or riveted in an aperture in said catcher element.

115 The catcher element 71 is best shown in its retracted position in Figures 3 and 12 of the drawings, and it is from and back to this position that said element is actuated in the 120 operation of the machine as will now be set forth.

When the operating lever 33 is depressed by the operator, the tubular member 14 moves downward therewith on the guide tube 13, during which actuation the presser-foot 25 comes in contact with the topmost layer of the pile of cloth that is laid over the base-plate 1, while the needle 19 continues on downward through the pile and at the termination of its down stroke the point of the 10 needle is in very close proximity to the top face of the work-table, as hereinabove first described.

Just before the point of the needle 19 enters the opening 57 in the base-plate 1, the 15 catcher element 71 is moved forward and is brought to rest substantially in the position shown in Figure 13 of the drawings. This is brought about by the actuation of mechanism interposed between said slide-bar 65 20 and the operating lever 33, now to be described.

This mechanism comprises a rocking lever 77 that is pivotally mounted on the standard 5, as at 78 (see Figures 1 and 4), and is provided with a suitable spring-pressure device 79 to maintain some, although not excessive, tightness in the pivot, which will offer some 25 resistance but not interfere with an easy operation of the machine. The lower end portion of this lever extends through a slot 80 (see Figures 2 and 15) in the base-plate 1 and normally abuts the rear end of said slide-bar 65 near one corner thereof so that the adjacent side face of said lever 77 and longitudinal edge portion of the bar are in substantially the same plane, as best shown in Figures 3, 15 and 16 of the drawings.

Pivottally attached to the upper end portion of said lever 77, as at 81, is a reciprocatory bar 82 whose forward end portion slides with both an endwise and up and down movement under a guide-plate 83 which is secured to the side face of the arm 6 of the standard 5 by screws 84 (see Figures 1, 4, 18 and 19). 40 This reciprocatory bar 82 is yieldably held in normal forward position and with its forward end raised, as shown in Figures 1 and 18, by a spring 85 that has one end attached to a stud 86 on said arm 6 and its opposite end attached to another stud 87 on said bar 82. The forward position of the bar 82 is limited by a spring-stop member 88 on the standard 5 against which the lower end portion of the rocking lever 77 normally bears, 45 said stop member 88 also serving as a cushion when the bar 82 is snapped forward after actuation as will be presently set forth more clearly.

The reciprocatory bar 82 has its upper edge 60 portion notched by being cut away on an incline, as at 89, affording a shoulder 90, said shoulder being engaged by the end portion 91 of a downward right angular extension 92 of said operating lever 33 (see Figures 1 and 4) or, as shown in Figures 18 and 19, by

an insert 91^a at the end of said member 92 of the operating lever, in which latter modification a wear-plate 90^a is secured on said bar 82 coincident with the shoulder 90, both the insert 91^a and the wear-plate 90^a being obviously made of hardened metal to resist wear due to the frequent contact and rubbing action of the one part upon the other in the operation of the machine.

Normally, the end portion 91 or 91^a, as the case may be, of the lever arm 92, sets some distance ahead of the shoulder 90 or wear-plate 90^a, respectively, of the bar 82; and the space between them is so proportioned that, upon the down stroke of the lever 33 and just before the needle 19 has entered the opening 57 in the base-plate 1, the lever arm 92 will have engaged the bar 82 and moved the latter rearwardly, thereby rocking the lever 77, which latter in turn pushes the slide-bar 65 forward, so that the catcher member 71 moves forward and at the completion of the down stroke of the operating lever it is in substantially the position shown in Figure 13. This actuation of the catcher shifting mechanism 90 while the part 90 or 90^a, as the case may be, is still engaged by the part 91 or 91^a, causes the catcher element 71 to move a slight distance further than the position shown in Figure 13, and, as the part 91 or 91^a rides in an arc of a circle from the axis of the operating lever, it is released in due time from engagement with the part 90 or 90^a, at which time the hooked end portion 93 of a supplemental extension 94 of the lever arm 92 has swung 95 downward into position ahead of a stop member 95 on the reciprocatory bar 82, and the instant said bar 82 is released from the lever arm 92 the spring 85 which has been stretched during this operation reacts quickly and 100 draws the bar 82 forward until said stop member 95 engages said hooked end portion 93 of the supplemental extension arm 94 of the operating lever (see Figure 4 of the drawings). In some cases, in order to relieve the mechanism of shock, it may be preferably to provide, in lieu of the rigid hook portion 93, a spring element 93^a that is secured at its upper end portion to the angular projection 96 of said lever extension arm 94, as at 97, 105 110 said spring element 93^a resting normally flatwise against said angular extension 96 with its free end portion projecting downward so as to function like the above described hook portion 93. This spring element 93^a is held 115 against lateral displacement on said angular extension 96 by being provided with a longitudinal slot 98 through which projects a stud 99 from the angular extension, as more clearly shown in Figure 18. In connection with 120 this modification, which is illustrated in detail in Figures 18 and 19 of the drawings, the stop member 95 is provided with an undercut notch 95^a, with which latter portion 125 said spring element 93^a engages (see Figure 19).

19) when the bar 82 is snapped forward by said spring 85 as the end portion 91^a rides out of engagement with the wear-plate 90^a. In this action, should the stop member 95 strike the spring element 93^a with considerable force, the latter will yield so as to cushion the blow and it being somewhat stronger in tension than said spring 85 returns to its normal position against said angular extension 96 and brings the bar 82 to the proper position to hold said catcher element 71 in the position shown in Figure 13 of the drawings, the spring 68, of course, retracting said slide-bar 65 and keeping the rear end of said bar in contact with the lower end portion of said rocking lever 77.

The catcher element 71 is bifurcated, one of its arms 100 being straight and having a boss or lug 101 at its end in which is secured 20 a needle or pointed pin 102 constituting the thread hook. The other arm 103 has its outer end portion 104 turned inward towards the opposite arm 100 at an angle to afford an oblique cam face 105 and a restricted mouth 106 between the outer ends of said arms 100 and 103. The slide-bar 65 has a notched portion 107 which is engaged by the stud 72 on the catcher element 71 under the action of the spring 73 at any time said catcher element 25 is moved forward out of the effective range of the stop-pin or stud 75, so as to limit the laterally swung position of the catcher element, as shown in Figure 13 of the drawings.

35 After said catcher element 71 has been moved forward as above described by the actuation of the mechanism during the down stroke of the operating lever 33, and while it is moving to the excessive distance beyond the 40 position shown in Figure 13, just before the part 91 or 91^a rides out of engagement with the part 90 or 90^a, as the case may be, the needle 19 moves through the opening 57 in the base-plate 1 and down between the arms 100 and 103 of said catcher element 71, and the 45 point of the needle reaches a point considerably below the under side of said catcher element just before the reciprocating bar 82 is snapped forward by the spring 85 and the 50 stop member 95 engages the hook 93 or spring element 93^a and thereby positions the catcher element in the relation to the needle 19 as shown in Figure 13.

When the operating lever 33 starts on its 55 upward stroke, the needle 19, of course, moves upward therewith, and, at the same time, the catcher element moves rearwardly, its cam portion 105 riding across the needle and thereby swinging the arm 100 of the catcher 60 element towards the needle. As the needle rises the loop of the stitching thread that has been carried by the needle down through the pile of cloth opens from the side of the needle towards the arm 100, and the 65 needle or pin 102, by the action of the

cam portion 105 riding across the needle 19, is swung into position to engage the opened loop of the thread. The reason that the loop opens to the side of the needle towards the arm 100 of the catcher element 71 70 is that the arm 103 of said element being in close contact with the opposite side of the needle the loop is thereby prevented from opening towards said arm 103. This being the case, just as soon as the hook 91 or the 75 spring element 91^a is released from engagement with the stop member 95 the spring 85 retracts the bar 82 and returns the rocking lever 77 to normal position, and at the same time the spring 68 retracts the slide-bar 65 80 with a sudden movement, during which the catcher element 71 is moved into substantially straight axial alinement with respect to the longitudinal axis of the bar 65 owing to the action of the cam portion 105 on the 85 needle before the latter has been raised sufficiently to clear said catcher element, and upon the continued rearward movement of the said bar 65 said catcher element rides in contact with the stud or stop pin 75 which 90 maintains said alinement of the catcher element with the bar, thereby drawing with it the loop of the thread which has been caught by the needle or pin 102 on the arm 100 of the catcher element. Thus, the needle 19 continues upon its upward stroke, leaving the stitching thread looped through the pile of 95 cloth.

The opening of the loop of stitching thread, as above described, is further facilitated by 100 the pressure of the presser-foot 25 on the pile of cloth during the initial upward stroke of the needle 19, and, to maintain such pressure on the pile during the first part of the upward movement of the needle so as to insure 105 the opening of the loop of thread, provision is made for locking the bar 37 that carries said presser-foot 25 during the period in which the loop is being opened. This is accomplished in a very practical and satisfactory manner by providing the lower portion of said bar 37 on its side adjacent to the tubular guide member 13 with a series of comparatively fine, though well defined, substantially V-shape serrations 108, with which a 110 correspondingly toothed detent or latch element cooperates. As shown, the detent or latch element comprises a slidable block 109 working in a transverse slideway in the plate 11 which supports the tubular guide member 13 (see Figures 5 and 10 of the drawings), said block having serrations 110 at its end contiguous to said bar 37, and said block being of a length so that when its toothed end portion is in interlocked engagement with the toothed portion of said bar 37, its opposite end is flush with the adjacent face of the bore 22 in the cylindrical extension 12 of said plate 11, so that the needle-carrying bar 18 115 can slide freely through said bore 22, and 120 125 130

during the time that said bar 37 is sliding through the bore said block is held in locking engagement with the bar 37 and the latter is held from up or down movement.

In order to limit the endwise movement of said block 109 it is provided on its under side with a longitudinally slotted recess 111 with which cooperates a stop in the form of a pin or stud 112 secured tightly in an aperture provided therefor in said plate 11, through which it is inserted from the bottom. Normally, before the needle-bar 18 is in the bore 22 of the cylindrical extension of said plate 11 so as to abut the adjacent end of said block 109, the block is freely movable endwise and the needle-bar 18 is readily movable up and down as its teeth 108 will ride out of engagement with those 110 of said block 109, which latter member is then moved endwise away from said bar 37 and its end portion is accordingly projected into the bore 22, as shown in Figures 5 and 10. This position of the block 109, of course, is limited by the slot-and-pin arrangement between the block 109 and the plate 11, and, therefore, in order to afford ample clearance of the lower end portion of the needle-bar 18, the latter is cut away on the side thereof towards said block 109, as at 113, said cutaway portion having its face either tapered directly from the end of the needle-bar, or, preferably, as shown in Figures 4 and 5, extending for a short distance from the end straight and substantially parallel with the longitudinal axis of the bar and then gradually turning outward to the normal peripheral face of the bar, thereby forming a cam portion 114.

By the above noted construction and arrangement, the presser-foot 25 travels downward simultaneously with the needle 19, as hereinabove described, in substantially the same relation as shown in Figures 1 and 5, and until said presser-foot has been arrested by coming in contact with the pile of cloth and it has compressed that portion of the pile thereunder to a considerable extent by the power of the spring 41, which latter yields and permits the needle to continue on through the pile of cloth. As soon as the cam portion 114 of the needle-bar 18 reaches the projecting end portion of the detent block 109 it acts thereagainst to move said block towards the carrier-bar 37 of the presser-foot, and as the teeth 108 of the latter are engaged by those 110 of the block, the presser-foot is securely held in its contacting position with the pile of cloth during the completion of the down stroke of the needle and also during the return upward stroke of the needle until such time as the cutaway portion 113 comes opposite the block 109, after which the spring 41 is free to function in restoring the carrier-bar 37 to its normal position relative to the needle 19 and its carrier parts during the balance of the up stroke. This obviously prevents the lift-

ing of the presser-foot, in any case, no matter how thick the pile of cloth, until the needle has moved upwardly initially a distance to effect the opening of the loop of the stitching thread with sufficient positiveness to insure it always being caught by the catcher element 71 upon each actuation of the machine. Without such provision for locking the presser-foot the elasticity of some cloth is such as to overcome the tension of the spring 41, especially while the needle is backing out of the pile on its up stroke, and this reaction of the compressed portion of the pile through which the stitch is made, in some cases, tends to draw the looped thread up with the needle and thereby prevents the opening of the loop at all or at least sufficiently to permit it being readily engaged by the catcher element 71.

In other machines of the character of the present invention, as far as the inventor is aware, the release of the catcher element from the loop of the stitching thread, after the completion of the stitch, is brought about through a manual manipulation of some part of the actuating mechanism of the catcher element, and in some machines this mechanism has to be reset manually to normal condition after each operation of the machine in making a stitch before a second stitch can be made. In this machine provision may be made for the manual release of the catcher element from the loop of stitching thread and for restoring the mechanism to normal condition, and, accordingly, for this purpose, the reciprocating bar 82 is provided at its forward end with a laterally projecting angular extension or ear 115 in cooperative relation to another like extension or ear 116 on the guide-plate 83 (see Figures 1, 4, 18 and 19 of the drawings) which may be conveniently grasped between the thumb and forefinger of the operator so as to thereby press the ear 115 towards the ear 116 and in that way move the bar 82 rearwardly and, of course, rock the lever 77 which in turn actuates the slide-bar 65 and moves the catcher element 71 forward to a position out of effective range of the stop pin or stud 75, whereby said catcher element is swung, by the action of the spring 73, laterally, as shown in Figures 13 and 14, and whereby the catcher-needle or pin 102 is withdrawn from engagement with the loop of the stitching thread automatically during this last above described actuation of the parts, or, in case the thread does not become so disengaged by the needle or pin 102, it is readily pulled therefrom by the operator if he keeps the two ears 115, 116, pressed together as above described, and with his other hand pulls upon the looped thread from above the base-plate 1. In either case, the disengaged loop is withdrawn through the opening 57, by the operator.

Provision, however, is preferably made for a substantially automatic release of the thread

from the catcher element after each operation of making a stitch. For this purpose, a latch element 117 is pivoted, as at 118, on the under side of the base-plate 1 alongside of the lower end portion of the rocking lever 77 and rear end portion of the slide-bar 65 (see Figures 3, 15 and 16 of the drawings). This latch element is normally pressed yieldably towards said rocking lever 77 and slide-bar 65 by a spring 119 which is secured tightly at one end by the screw 67 that fastens the rear guide-plate 66 in place, while its free end portion bears against an angular end extension 120 of the latch element. At the side of the latch element towards said rocking lever 77 and slide-bar 65 is a lateral projection 121 affording a substantially square forward shoulder 122, and having a compound curved rear portion 123 affording a cam surface.

Normally, in retracted position of the slide-bar 65, the lateral projection 121 of the latch element 117 bears against the edge of said slide-bar near the rear end thereof, and as the side face of the rocking lever 77 is located practically flush with the corresponding edge of the slide-bar 65, any joint forward and backward movement of said rocking lever and slide-bar in their cooperative actuation will not permit any locking engagement of the latch member behind the end of the slide-bar. That is, when the rocking lever 77 pushes the slide-bar 65 forward, as shown in Figure 15, so as to bring the catcher element 71 to the position shown in Figure 13, the lateral projection 121 of the latch element 117 is in slidable engagement with the face of said rocking lever, and upon the return of said rocking lever to normal position and it being followed by the slide-bar under the action of the spring 68, the slide-bar rides by said lateral projection 121 of the latch element without any interference thereby. However, if said slide-bar 65 is moved forward independently of said rocking lever, as shown in Figure 16, then the lateral projection 121 of said latch element 117 snaps behind the end of the slide-bar and prevents the return of the latter to normal position until released from such engagement. In this position of the slide-bar 65 the catcher element 71 is in the position shown in Figure 14 of the drawings, in which position of the catcher element the needle or pin 102 is withdrawn from the loop of the stitching thread. Therefore, it is obvious that if the loop of the thread, while still engaged by the catcher element 71 and the latter is in its retracted position as shown in Figures 3 and 12, is pulled by the operator, the slide-bar will be thereby drawn forward with the catcher element 71 in a position slightly ahead of that shown in Figure 14 of the drawings, or, in other words, with the needle or pin 102 just about in register with the opening 57, in which position, while it is still held by the looped thread in the operator's hand, and against the tension

of the spring 68, the catcher element is substantially in straight, longitudinal, axial alignment with the slide-bar 65, as shown in Figure 12, and at which time the rear end of said slide-bar is just a short distance ahead of 70 the lateral projection 121 of the latch element 117, so that the latter is free to move behind the slide-bar and thereby stop the latter from moving back to normal position when the operator lets go of the thread or permits it to 75 become slack between his hand and the catcher-needle or pin 102. Therefore, when the operator does release his hold on the thread or permits it to become slack as above set forth, the needle or pin 102 is released from engagement with the loop of thread as the spring 73 swings the catcher element 71 to the angular position shown in Figure 14 of the drawings, and, obviously, the looped thread is then free to be withdrawn out through the opening 57. 80

From the above it is clearly apparent that a substantially automatic release of the thread from the catcher element is readily accomplished by the operator merely pulling upon the looped thread after the stitch is completed, 90 then easing up and slackening the thread, after which the loop is withdrawable at will.

In this connection, it may be here stated that, with the parts still in the position shown in Figures 14 and 16, after the thread has been 95 withdrawn as above described, the machine can be operated to make the next succeeding stitch without restoring the parts to their normal condition as shown in Figures 3, 11 and 12, because, when the rocking lever 77 is actuated upon the depression of the operating lever 33, as first above described, its lower end portion, during the forward movement thereof, first engages the cam portion 123 of the lateral projection 121 of the latch element 117, thereby swinging the latter so as to move the shoulder 122 from behind the slide-bar 65, and the continued forward movement of the rocking lever 77 in engagement with said slide-bar 65 moves the latter forward as first 100 described in the operation of making the stitch. 105

It may be here further stated, that while the loop of the stitching thread may be released from the catcher element 71 by the manual operation effected by the operator pressing the ear 115 of the reciprocating bar 82 towards the ear 116 of the guide-plate 83, or through the process of pulling the slide-bar 65 forward by the loop of thread when the latter is hooked on the catcher-needle or pin 102, as above described, the release of the loop of thread from said needle or pin 102, may also be readily and conveniently accomplished by the operator merely depressing the operating lever 33 to effect the forward actuation of the slide-bar 65 and thereby carry the catcher element 71 forward as in making the stitch, such operation of the operating lever, of course, being made after 115 120 125 130

the completion of the preceding stitching operation and after the cloth has been removed from under the needle 19, which removal is readily accomplished by the operator pulling the pile and during which the looped strands of the thread slide through the pile. In this operation the operator can conveniently hold the cloth with one hand while he manipulates the operating lever 33 with his other hand.

From the foregoing it is clearly apparent that the machine possesses all the advantages of those having only provision for the manual release of the thread loop from the catcher element, with the further advantage of an automatic release thereof.

While the structure and arrangement of the catcher element 71, as hereinabove described, serves its purpose quite well in general, it may be desirable in some cases, and possibly in all, to modify its construction and arrangement somewhat. A practical modification, therefore, is illustrated in Figure 17 of the drawings, in which, in lieu of the stop-pin 72 and the cooperating notched portion 107 of the slide-bar 65, the catcher element 71 is provided with an arm 124 extending rearwardly in line with the arm 100 thereof and parallel to the edge of the slide-bar 65, said arm having a substantially right angular projection 125 at its end and being spaced from the slide-bar 65 when the arm 100 of the catcher element is in cooperative engagement with the stop-pin or stud 75 in the normal retracted position of said catcher element, as shown in full lines in Figure 17. In this modification the arm 103 of the catcher element has its outer end portion straight and substantially parallel with the arm 100, as at 126, the cam portion 105 being located approximately midway between this end portion 126 and the base portion of the arm.

The inner edge portions of the cam 105 and the end 126 of the arm are flanged, as at 127, so as to afford a wider bearing face to ride across the needle 19 and thereby further insure that the loop of the stitching thread will not open at that side of the needle.

In lieu of the helical spring 73 of the first above described structure, an arcuately bent wire spring 128 is provided in this modification, said spring 128 being obviously secured tightly to the outer end portion of the flange 127, as by arcuating the end portion of the spring and squeezing it in a slit or groove provided therefor in said flange, as at 129, the opposite end portion of the spring being hooked in an aperture provided therefor in the slide-bar 65, as at 130.

The respective positions of the catcher element just above described, corresponding to its actuations in the operation of the machine as illustrated in Figures 13 and 14 of the drawings, are indicated by the dotted lines 65 in Figure 17.

At this point it may be stated that the opening in the ring portion 26 of the presser-foot 25, afforded by the slot 27, as shown in Figure 9 of the drawings is to permit the withdrawal of the looped strands of the stitching thread from the ring readily and conveniently after the completion of the stitch and in order to facilitate the severing of the thread on a cutting device to be presently described. This opening 27 also facilitates placing the end portion of the thread drawn through the eye of the needle 19 by the operator prior to making a stitch, over the top side of the ring, which would otherwise be difficult to do if the ring were continuous and not split as shown, because the length of thread extending from the eye of the needle, after severance of the thread following the completion of the preceding stitch, would be hanging down through the ring and it would be quite troublesome to bring it back up through the ring so as to be laid over the top side thereof as is desirable and, in fact, practically necessary in the proper operation of the machine.

As shown in Figures 3, 15 and 16 of the drawings, a stop member 131, similar to the stop member 88 for the rocking lever 77, is located in abutting relation to the rear end of the slide-bar 65 in the normal retracted position of the latter, said stop member 131 possessing a certain inherent resiliency so as to serve as a cushion when the slide-bar 65 is forcibly retracted by the spring 68, and said stop member 131, by its relative location, relieves the rocking lever 77 of considerable shock as the latter is thereby guarded from being struck directly by said slide-bar 65 should the latter be snapped back to normal position at any time while said rocking lever is in its own normal position.

These two stop members 88 and 131 may be of any desirable form, but, as shown more clearly in Figure 2 of the drawings, they each comprise a substantially U-shape piece of spring metal, one leg of which has an angular extension that is secured to the standard 5 or the bottom of the base-plate 1, as the case may be, by a screw or rivet, the opposite leg thereof being free and constituting the resilient engaging portion of the stop.

The thread-cutting device will now be described. It comprises a bracket member or plate 132 which is secured to the side of the head portion 7 of the arm 6 of the standard 5, as by screws 133 (see Figure 8), said bracket member projecting beyond the end of said head portion 7 and having its upper and lower margins notched, as at 134, with upper and lower projections 135 adjacent to said notches and over which projections the thread to be cut is hooked.

Cooperating with said bracket member 132 is a supplemental plate 136 corresponding in marginal outline and shape therewith, and between the two members 132 and 136 an or-

dinary relatively thin safety razor blade 137 is clamped by a knurled thumb-screw or other suitable fastener 138, said razor blade affording cutting edges coincident with the notches 134 so that the thread may be applied either to the top or under side of the cutting device to be severed. In this connection, also, it may be here stated that the additional guiding means for the stitching thread, hereinabove stated as being possibly desirable between the eye 64 on the arm 6 of the standard 5 and the eye of the needle 19, in some cases, is afforded by said thumb-screw 138, as the thread may be carried over the annularly grooved middle portion 139 thereof, or, obviously, said thumb-screw may have a transverse aperture 140 therethrough and through which the thread may be passed from said guide 64 to the eye of the needle.

In order to afford sufficient head room for the operation of opening the loop of the stitching thread and to facilitate the functioning of the catcher mechanism under the base-plate 1, the latter is preferably provided with a rectangular opening 141 as shown in Figures 3, 11 to 14, inclusive, and Figure 17 of the drawings, over which opening is placed a supplemental cover-plate 142 (see Figures 1, 2, 4, and 11). The hereinabove mentioned aperture 57 is located in this cover-plate 142 and it is preferably provided with a bushing 143 whose flange portion is neatly rounded so as to guide the point of the needle 19 into the aperture 57 should the needle become sprung slightly out of its normal straight alinement. This cover-plate 142 is preferably secured in place by screws 144 inserted from the under side of the base-plate 1 as shown in Figure 3 of the drawings.

Obviously, instead of merely cutting away or reducing the lower end portion of the needle-carrying bar 18 at one side only, to produce the cam portion 114 which cooperates with the detent 109, as shown in Figures 4 and 5 of the drawings, said bar 18 may be reduced in diameter all around in the same region, thereby making the cam portion 114 annular. In this way, no particular care need be exercised in setting the needle-carrying bar in position as is required when it is cut away or reduced from one side only. It is further obvious that many other changes in the general construction and arrangement, as well as in the details of the several parts of the machine individually, may be made and substituted for the construction and arrangement herein shown and described, without in the least departing from the spirit and scope of the invention as defined by the appended claims.

What is claimed is:

1. In a stitching machine, a spring-pressed presser-foot, a reciprocating needle-carrier cooperating to actuate said presser-foot, and means controlled by the needle-carrier for locking said presser-foot in compressing relation to the top of a pile of cloth being stitched during the descent of the needle through the cloth and during the initial part of the return upward movement of the needle. 70
2. In a stitching machine, a spring-pressed vertically reciprocable carrier-bar having a presser-foot at the lower end thereof, a cooperating vertically reciprocable carrier-bar having a sewing needle at its lower end in alinement therewith, and a detent working transversely between said two mentioned carrier-bars, said detent having provision for an interlocking engagement with the carrier-bar for the presser-foot but being normally releasable from such engagement and permitting reciprocation of said carrier-bar, and being slidably engageable by said carrier-bar for the sewing needle after the presser-foot has come in compressing relation upon the goods being stitched whereby to lock said carrier-bar for the presser-foot during a continued downward movement of the carrier-bar for the needle and during the initial part of the return upward movement of the latter. 80
3. In a stitching machine, a vertically reciprocable carrier-bar having a presser-foot at the lower end thereof, said bar being provided with a series of serrations extending transversely of the lower end portion thereof, a cooperating vertically reciprocable carrier-bar having a sewing needle at its lower end, and a detent slidably mounted between said two mentioned carrier-bars, said detent being provided with serrations at its end adjacent to said carrier-bar for the presser-foot whereby to engage the serrations of said carrier-bar, but said detent being freely movable out of engagement with said carrier-bar during a normal simultaneous downward movement of said two mentioned carrier-bars until the presser-foot has come into compressing relation upon the goods being stitched, but being moved into interlocking engagement with said carrier-bar for the presser-foot by a sliding engagement of said detent by said carrier-bar for the needle during a continued downward movement of said last mentioned carrier-bar and during the initial part of the return upward movement thereof. 100
4. In a stitching machine, a base-plate, a standard on said base-plate, said standard having an arm overhanging said base-plate, a tubular guide member extending upward from the outer end portion of said arm, a second tubular member fitted to reciprocate slidably on said tubular guide member, a carrier-bar secured at its upper end portion axially in said reciprocatory tubular member, a sewing needle secured to the lower end portion of said carrier-bar and extending axially therefrom, means for guiding said carrier-bar through said tubular guide member, 120
5. In a stitching machine, a base-plate, a standard on said base-plate, said standard having an arm overhanging said base-plate, a tubular guide member extending upward from the outer end portion of said arm, a second tubular member fitted to reciprocate slidably on said tubular guide member, a carrier-bar secured at its upper end portion axially in said reciprocatory tubular member, a sewing needle secured to the lower end portion of said carrier-bar and extending axially therefrom, means for guiding said carrier-bar through said tubular guide member, 130

a second carrier-bar paralleling said first mentioned carrier-bar in cooperative relation thereto and being reciprocable through a guide opening in said arm of the standard, 5 a lateral extension on said reciprocatory tubular member and having a guide opening therein through which said second mentioned carrier-bar is slidably, a presser-foot on the lower end portion of said second mentioned carrier-bar, a spring coiled about said second mentioned carrier-bar between said arm of the standard and the under side of said lateral extension of said reciprocatory tubular member whereby to yieldably hold 10 the latter in normal raised position, a stop on said second mentioned carrier-bar in cooperative relation to the upper side of said lateral extension to limit said normal raised position of the latter, a spring co-acting with second mentioned carrier-bar and said lateral extension to yieldably hold the stop on said second mentioned carrier-bar in engagement with said lateral extension, and an actuating handle-lever having an operable connection 15 with said reciprocatory tubular member.

5. In a stitching machine, a vertically reciprocable needle-carrier, a lateral bracket extension thereon having an opening therethrough, a cooperating presser-foot-carrier reciprocable parallel with said needle-carrier and being guided slidably through said opening in said lateral bracket extension thereof, a spring acting upon said lateral bracket extension whereby to yieldably hold said 20 needle-carrier in normal raised position, a stop on said presser-foot-carrier in cooperative relation to the lateral extension of said needle-carrier, and a spring co-acting with said presser-foot-carrier and said lateral extension whereby to yieldably hold said stop on the carrier in normal supporting engagement with said lateral extension.

6. In a stitching machine, cooperating reciprocatory needle and presser-foot carriers, 45 and means controlled directly by the needle-carrier during its stitch-forming stroke for locking the presser-foot-carrier after the presser-foot has come in compressing relation upon the cloth being stitched and for holding 50 the presser-foot in such relation during the completion of the stitch-forming stroke of the needle and during the initial part of the receding movement of the needle.

7. In a stitching machine, a base-plate, a 55 standard thereon, said standard having an arm overhanging said base-plate, a needle-carrier and a presser-foot-carrier reciprocable on said standard arm in cooperative relation to said base-plate, a sewing needle extending 60 from the end of said needle-carrier in alignment therewith and being adapted to carry a loop of thread through goods being stitched, said base-plate having an aperture therein for the reception of said needle, a loop-catcher 65 mounted on the under side of said base-plate

in correlation to said needle-receiving aperture therein, said loop-catcher comprising a laterally swingable bifurcated element, one arm of which carries an inwardly projecting hook member, the other arm having its end portion turned inwardly affording a restricted throat in the region of said hook member of said first mentioned arm and a cam portion on said second mentioned arm between said throat and the base portion of the element, a spring-retracted reciprocatory bar to which said bifurcated element is pivotally attached, a rocking lever on said standard, the lower end portion thereof extending through a longitudinal slot in said base-plate and abutting the end of said reciprocatory bar, and the upper end portion thereof being pivotally connected to a longitudinally reciprocable bar on said arm of the standard, a spring for normally holding said last mentioned bar in 80 forwardly retracted position, said bar having an actuating shoulder thereon and a correlated stop shoulder intermediate said actuating shoulder and the forward end portion of the bar, and a bell-crank operating lever 85 mounted on said arm of the standard, one arm of said lever being engageable with said actuating shoulder of said last mentioned reciprocable bar and having a hooked extension to engage said stop shoulder on said bar, and the other arm of said lever being cooperatively attached to said needle-carrier and presser-foot-carrier whereby to effect a cooperative actuation of said two carriers, said mechanism being relatively proportioned and timed so that, 90 upon the depression of the operating lever, the catcher-element moves forward and swings laterally so as to straddle said needle-receiving aperture in said base-plate with the cam-arm of said catcher-element contiguous to the path of the needle and prior to the passage of the needle into said aperture, the needle-carrier and presser-foot-carrier being so correlated and yieldably connected that they move simultaneously towards said base-plate 95 until the presser-foot comes in compressing relation upon the goods being stitched, whereupon the needle continues through the goods and into said aperture in the base-plate in cooperative relation to said catcher-element, 100 and upon the release of power of said operating lever, the catcher-element's cam portion rides across the ascending needle and thereby 105 effects the engagement of the hook member of said element with the loop of stitching 110 thread as the latter opens.

8. In a stitching machine, a loop-catcher mechanism, comprising a reciprocatory actuator-bar yieldably held in retracted normal position, a second reciprocatory actuator-bar also yieldably held in retracted normal position, a catcher element on said second mentioned actuator bar, a rocking lever operably connected to said first mentioned actuator-bar and having an abutting actuating relation to 115

5 said second mentioned actuator-bar, a lever device for operating said first mentioned actuator-bar from normal retracted position and said bar being also directly actuatable independently of said lever device to actuate said 10 rocking lever and in turn operate said second mentioned actuator-bar from its normal position, and a latch-element correlated to said rocking lever and said second mentioned actuator-bar whereby said bar may be directly operated from its normal position and held from complete return to such position until a 15 subsequent actuation of said rocking lever releases said latch-element.

15 9. In a stitching machine, a loop-catcher comprising a reciprocatory bar yieldably held in retracted normal position, a bifurcated catcher-element pivotally mounted on the forward end of said bar so as to swing laterally 20 thereof, one arm of said element having an inwardly projecting hook member, and the other arm thereof being turned toward said first mentioned arm to afford a restricted throat between the end portions of the arms 25 and a cam portion intermediate the end and base portions of said second mentioned arm, and a sewing needle reciprocable at substantially right angles to the path of movement of 30 said catcher-element, said catcher-element being moved forward and swung laterally to a position where its cam portion is contiguous to the path of the sewing needle, the needle being next moved into cooperative relation between the arms of the catcher-element, and the 35 catcher-element being next retracted and withdrawn from the needle while the latter is still in cooperative engaging relation with the cam-arm of the catcher-element and during the initial part of the receding movement 40 of the needle, whereby the stitching thread loop is opened towards the hook member of the catcher-element and is caught by the latter.

45 10. In a stitching machine, a loop-catcher comprising a reciprocatory bar yieldably held in retracted normal position, a bifurcated catcher-element pivotally mounted on the forward end of said bar so as to swing laterally 50 thereof, one arm of said element having an inwardly projecting hook-member, and the other arm thereof being turned toward said first mentioned arm to afford a restricted throat between the end portions of the arms and a cam portion intermediate the end and 55 base portions of said second mentioned arm, a sewing needle reciprocable at substantially right angles to the path of movement of said catcher-element, said catcher-element being movable forward and swung laterally to a 60 position where its cam portion is contiguous to the path of the sewing needle, manually operable means for effecting a correlated actuation of said reciprocatory bar and said sewing needle whereby said catcher-element is

65 placed in said described forward position prior to the positioning of the sewing needle, said means having provision for the release of said reciprocatory bar after the sewing needle has been moved to cooperative engaging relation with the cam portion of said catcher-element and during the initial part of the receding movement of the needle whereby the stitching thread loop is opened towards the hook-member of the catcher-element and is caught by the latter, means for 70 actuating said reciprocatory bar manually and independently of said sewing needle to move said catcher-element to its forward position as first above described, said reciprocatory bar being also movable to bring said catcher-element to said described forward position by pulling the engaged thread-loop, and a latch-element engageable with said reciprocatory bar in the forward position thereof when actuated as last above described, said latch-element being released from such engagement by the subsequent operation of either of said two above mentioned manual 75 actuations of said reciprocatory bar.

80 11. In a stitching machine, a loop-catcher mechanism comprising a reciprocatory bar yieldably held in retracted normal position, a catcher-element on said reciprocatory bar, means for manually actuating said bar forwardly to move said catcher-element into 85 position to engage the thread-loop, said bar being also actuatable by pulling the engaged thread-loop, and a latch-element engageable with said bar when actuated as last described whereby to hold the bar with the catcher-element in position to release the thread-loop, said latch element being released from engagement with the said reciprocatory bar by a 90 subsequent manual actuation of said bar.

95 12. In a stitching machine, stitch-forming mechanism including a reciprocatory sewing needle adapted to take a loop of thread through the goods to be stitched, a loop-catcher cooperating with said needle to engage and hold the thread-loop during the receding stroke of the needle, means for manually actuating said needle and loop-catcher in correlation to each other to effect the engagement of the thread-loop by the loop-catcher, said means being subsequently operable to effect the release of the loop-catcher from the thread-loop after removal of the goods being stitched from the machine, a 100 part of said manually operable means being actuatable to move the loop-catcher independently of the needle to effect the release of the thread-loop, and said loop-catcher being operable to effect such release by pulling the engaged thread-loop, and a latch-element engageable with said loop-catcher to hold it in releasing position when actuated as last 105 described, said latch-element being released from engagement with said loop-catcher by a 110 115 120 125

subsequent operation of said manually operative means by either of the two described processes.

13. In a machine of the character described, 5 means for carrying a loop of thread through goods, and means for catching the loop after it is passed through the goods, said loop-catching means including a yieldably held retractive element to engage and hold the loop and being actuatable to disengage the loop by 10 first pulling and subsequently releasing the looped thread.

14. In a machine of the character described,

means for carrying a loop of thread through goods, and means for catching the loop after 15 it is passed through the goods, said loop-catching means including a yieldably held retractive element to engage and hold the loop, a manually operable mechanical device for actuating said element to disengage the loop, 20 said element being also directly actuatable independently of said mechanical actuating device to disengage the loop by first pulling and subsequently releasing the looped thread.

JOHN B. GURY, JR.
